UNITED STATES PATENT OFFICE.

THOMAS H. SIMPSON, OF DETROIT, MICHIGAN.

CAR-COUPING.

SPECIFICATION forming part of Letters Patent No. 595,351, dated December 14, 1897.

Application filed August 20, 1897. Serial No. 648,915. (No model.)

To all whom it may concern:

Be it known that I, THOMAS H. SIMPSON, a citizen of the United States, residing at Detroit, county of Wayne, State of Michigan, have invented a certain new and useful Improvement in Car-Couplers; and I declare the following to be a full, clear, and exact description of the invention, such as will enable others skilled in the art to which it appertains to make and use the same, reference being had to the accompanying drawings, which form a part of this specification.

My invention has for its object certain new and useful improvements in car-couplers; and it consists of the construction, combination, and arrangement of devices hereinafter specified and claimed, and illustrated in the accompanying drawings, in which—

Figure 1 is an inverted plan view of the head of the draw-bar. Fig. 2 is a horizontal section on line 2 2, Fig. 3. Fig. 3 is a vertical section on the line 3 3, Figs. 1 and 2. Fig. 4 is a detail view showing the method of engaging the coupling-pin in the head, as illustrated in Fig. 1. Figs. 5, 6, and 7 are detail views illustrating modifications in the manner of engaging the pin in the head to hold the pin from rotation.

The objects of my invention include means for holding the coupling-pin from rotating in the head of the draw-bar or coupler and also means to strengthen the head of the draw-bar or coupler.

Owing to the strain upon coupling devices, and especially owing to the increased strain coming upon them in consequence of the growing tendency to enlarge the size and weight of cars, it becomes indispensably necessary to strengthen the draw-bars or couplers, in order that they may resist the increased strain. Furthermore, inasmuch as the heads of the draw-bars or couplers are commonly made of malleable iron, while the knuckles and pins are made of steel, there is an inevitable tendency for the locking-pin when it is permitted to rotate to wear the adjacent parts of the coupler-head, the malleable casting of the head being of softer metal. It is the purpose of my invention to remedy these difficulties and to provide means for securing the desired ends above referred to.

I carry out my invention as follows:

A represents the head of a draw-bar or coupler.

B is any ordinary knuckle, and C is a locking-pin carrying the knuckle in the head of the coupler or draw-bar.

To prevent the pin from turning, as illustrated in Figs. 1 and 4, the head of the coupler is provided with a shoulder a , slotted horizontally on opposite sides of the coupling-pin, as indicated at a' and a^2 , to permit the insertion of a key A' through a corresponding orifice in the base of the pin, the shoulders of the orifices a' and a^2 engage the key A' from 65 turning, and consequently hold the pin C from turning in the head. I would have it definitely understood, however, that my invention broadly contemplates holding the pin from turning in the head in any suitable manner and by any suitable means. Therefore my object may be accomplished by constructing the pin C with a flattened portion, (indicated in Fig. 5 at c,) said pin being cut away to form said flattened portion, the head being 75 formed with a corresponding shoulder (indicated at a^3) to engage the flattened face of the pin, or, as shown in Fig. 6, the pin C may be formed with a rib c' to engage in the corresponding keyway (indicated at c^4) in the 80 head, or, as indicated in Fig. 7, the pin C may be cut away at its lower end to form a squared end, (indicated at c^5), the head A being formed with a corresponding opening to receive the squared end of the pin. In these ways the 85 pin may readily be held from turning in the head and other means may be employed for accomplishing the same results within the scope of my invention. To prevent the locking-pin from turning in the head will obviously prevent wear upon the head, the knuckle rotating upon the pin. Neither do I limit the application of the means to hold the pin from turning to the lower end thereof, as it may thus be held by suitable means otherwise located. The key A' may be a split key or otherwise, as may be desired.

To strengthen the head, my invention contemplates the construction of the same on each side of the mouth A² of the head with 100 double walls, an outer wall A³ and an inner wall A⁴ on the side of the guard-arm A⁵ of the head, said walls being indicated in full lines in Fig. 3 and in dotted lines in Fig. 2.

The opposite side of the head carrying the knuckle is also constructed with an outer wall A⁶ and with an inner wall A⁷, (indicated in full lines in Fig. 3 and in dotted lines in Fig. 2,) said inner and outer walls A³ A⁴ and A⁶ A⁷ forming chambers therebetween, respectively, said chambers each being divided by a strengthening diaphragm or brace, said diaphragms or braces being shown at a⁵ and a⁶, the same serving to brace the two outer walls adjacent thereto above mentioned, while said diaphragms also brace the front and rear walls of each of said chambers on each side of the mouth of the coupler, said front and rear walls being indicated in Fig. 2 at a⁷ and a⁸. A head so strengthened may obviously be made of any desired degree of strength.

It will be observed that the inner wall on the adjacent side of the head stops the inward movement of the knuckle. Said inner wall may be of any suitable form.

It is evident that the inner wall of the double walls on each side the mouth extends from the forward end of the corresponding outer wall inward and rearward to the rear portion of the outer wall of the head continuously and unbroken to afford greater strength.

What I claim as my invention is—

1. A draw-bar or coupler head constructed with a mouth, and with double walls on each side of the mouth to strengthen the head, the

inner of said walls extending continuously from the forward portion of the outer wall to the rear thereof, for the purpose set forth.

2. A draw-bar or coupler head constructed 35 with a mouth and provided with double walls on each side the mouth, the inner of said walls extending continuously and unbroken from the forward portion of the corresponding outer wall inward and rearward to the 40 rear of the corresponding outer wall of the head, substantially as set forth.

3. A draw-bar or coupler head constructed with a mouth, and with double walls on either side of the mouth, said double walls united by 45 a horizontal connecting diaphragm or brace intermediate the top and bottom of said walls, for the purpose set forth.

4. A draw-bar or coupler head constructed with a mouth and provided with double walls 50 on each side of the mouth, the double walls on each side the mouth united by an inner horizontal connecting diaphragm or brace intermediate the top and bottom of said walls, for the purpose set forth.

In testimony whereof I sign this specification in the presence of two witnesses.

THOMAS H. SIMPSON.
